CLAIM

The ornamental design for an electrical suction lifting machine as shown and described.

DESCRIPTION

FIG. 1 is a front perspective view of an electrical suction lifting machine showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of an electrical suction lifting machine in another configuration.

Broken lines in the drawings depict portions of the electrical suction lifting machine that form no part of the claimed design.
